UNITED STATES PATENT OFFICE

102,125

DESIGN FOR A SHOE

Israel Berman, Little Falls, N. Y.

Application October 29, 1936, Serial No. 65,566

Term of patent 3½ years

To all whom it may concern:

Be it known that I, Israel Berman, a citizen of the United States of America, residing in Little Falls, county of Herkimer and State of New York have invented a new, original, and ornamental Design for a Shoe of which the following is a specification, reference being had to the accompanying drawing, forming part thereof,

Fig. 1 is a plan view of a shoe showing my new design.

Fig. 2 is a side elevational view of a shoe as shown in Fig. 1.

I claim:

The ornamental design for a shoe substantially as shown.

ISRAEL BERMAN.
